COMPOUND FEEDER

Philip D. Blanchard, Hammond, Ind., and Charles R. Hardy, Mount Vernon, N. Y., assignors to The Superheater Company, New York, N. Y.

Application October 26, 1933, Serial No. 695,258

5 Claims. (Cl. 210—29)

Our invention relates to an arrangement for introducing measured quantities of anti-scaling compound into boiler feed water and aims to provide a novel and efficient means for such purpose.

5 The present invention relates to the known type of apparatus having a conduit and including means for introducing anti-scaling compound into the water flowing in the conduit.

10 The novel features of the invention are pointed out in the appended claims. The invention itself, however, together with its objects and advantages, will best be understood from the following detailed description of a compound feeding arrangement in accordance with our invention, 15 such description having reference to the accompanying drawing and the arrangement illustrated in said drawing being selected by way of example from a number of possible embodiments of the invention. In the drawing,

20 The figure is an elevational view, partly in section, of a system, in general of known type, for supplying feed water to a locomotive boiler but having our compound feeding arrangement applied thereto.

25 The arrangement illustrated in the drawing includes a pump 10 having water cylinders 12, 12 and steam cylinders 14, 14. Pump 10 has an inlet pipe 16 for feed water and an outlet pipe 18. Pipe 18 delivers the water from pump 10 to a 30 steam heated feed water heater 19 from which the preheated water is conducted by pipe 20 to a check valve 22 and an inlet plug 24 assumed to be in the side of a locomotive boiler not shown. Exhaust steam is supplied to the heater 19 from the 35 engine cylinders (not shown) through a pipe 26. Exhaust steam from the pump cylinders 14 preferably also is conducted into the heater 19, a pipe 28 being shown for this purpose. Pressure steam for operating the cylinders 14 is supplied by a pipe 29 having a throttle valve 30 therein.

40 In an arrangement of the character just outlined, the main purpose for supplying anti-scaling compound is to prevent incrustation of the water surfaces on the exhaust steam feed water heater 19. For such purpose, we have provided in the arrangement illustrated a conduit 32 extending from the pipe 18 on the high pressure or delivery side of the pump 10 to the pipe 16 on the low pressure or inlet side of such pump. Conduit 50 45 32 includes a pipe 34 leading off from the pipe 18 and extending to a connection with the interior of a valve casing 36 within which is a valve 38 and a restricted opening or choke 40. When the valve 38 is closed, no water may flow through the conduit 32. It will be seen, also, that valve 38

closes against the pressure and a spring 42 is provided adapted to hold valve 38 seated against the pressure in the boiler to which pump 10 delivers feed water in case the check valve 22 should leak. The purpose of so holding the valve 38 against 5 fluid from a leaky check valve will presently appear. It is intended, however, that valve 38 shall be open whenever pump 10 is in operation and, to ensure that such will be the case, we provide a piston 44 connected to one end of the stem 46 of valve 38. Piston 44 works in a chamber within the casing 36 and, whenever pump 10 is working, piston 44 has steam pressure applied to one face thereof in a direction to overcome the spring 42 and open valve 38. Means for so supplying steam 10 to the piston 44 comprises a pipe 48 extending from the steam pipe 29 to the chamber 36. Pipe 48 is connected to pipe 29 at a point between the valve 30 and the pump 10 so that, when valve 30 is open, steam is supplied to operate piston 44 in 15 the manner described whereas, when valve 30 is closed to shut down pump 10, no steam is supplied to piston 44 and spring 42 then operates to close valve 38 and hold it closed until another 20 period of operation of the pump 10.

25 In the arrangement illustrated, the choke 40 is used to restrict the amount of water flowing through the conduit 32 to a small pre-determined amount. We do not, however, limit ourselves to a definite choke for limiting the rate of 30 flow through conduit 32 as the same general result can be obtained by merely using a long length of pipe having a small internal diameter to give the conduit a high resistance to flow. Said choke, when used, can conveniently be placed in 35 the same casing as the valve 38, as above indicated. By so doing, we find it feasible to guard against the clogging of the choke 40 by extending the spindle of valve 38 into the choke 40 as indicated at 46a. Therefore, whenever valve 38 is 40 moved in one direction or the other by spring 42 or piston 44, the fluid in the choke 40 is agitated and any solid which may have lodged in such choke is disturbed and may be washed out by the water flowing therethrough. It will be seen that 45 the choke 40 serves to relieve the remainder of the conduit 32 of the high pressure from the line 18 when the pump is in operation while valve 38 relieves the remainder of the conduit from such pressure when the pump is shut down, pipe 34 and 50 a portion of the casing 36 being the only elements of conduit always subject to the full pressure of pump or boiler.

55 From the casing 36, fluid which has passed the choke 40 is conducted by pipe 48 to a receptacle

50 within which is a chamber 52 for the anti-scaling compound. In the arrangement illustrated, we have indicated the use of anti-scaling compound in the form of solid blocks or bricks 54 and water flowing through the chamber 52 dissolved from the blocks 54 some tannin or other anti-scaling compound to be used to prevent incrustation in the heater 19. As shown, water from pipe 48 enters the top of chamber 10 52 and is distributed by strainer plate 56 so as to flow evenly over the blocks 54. Water from chamber 52 carrying the anti-scaling compound is conducted from the bottom of such chamber by pipe 58 to the induction pipe 16 of pump 10, 15 so that it is mingled with the stream going to the heater 19 and thence to the boiler. It will be seen that, for a given pressure between pipes 18 and 16 maintained by pump 10, a choke 40 of a given size, or its equivalent resistance will cause a pre-determined flow of water through 20 the conduit 32 and will therefore cause to be dissolved substantially constant quantities of compound from bricks 54 to produce a substantially constant strength of anti-scaling compound 25 in water flowing through pipe 18 to the heater 19.

However, if the chamber 52 were so located that the bricks 54 would stand under water when the pump 10 is shut down, they would dissolve more or less continuously to produce a 30 highly concentrated solution in chamber 52 and such solution would be discharged to the heater 19 almost immediately upon starting of pump 10, thus causing a waste of anti-scaling material. It is an important feature of our invention to prevent such a result. For this purpose, the chamber 35 52 is placed above the highest level 60 attained by the water in the source to which the pipe 16 is connected. In the arrangement illustrated, such source is assumed to be a tank in the 40 tender 62 of a locomotive. The chamber 52, moreover, is vented to atmosphere by pipe 64 which extends above the level 60 and contains a check valve 66 arranged to permit air from chamber 52 to escape to atmosphere when the 45 tank in tender 62 is being filled and to normally maintain atmospheric pressure in the chamber 52, but to prevent suction of air through the vent pipe 64 under abnormal circumstances, such as a partially choked line 16. It will be seen that 50 the bricks 54 are held normally above the water level in pipe 58 and are subject therefore, only to the dissolving action of the water which is sprinkled down on them from the plate 56, all water draining down below them when pump 10 55 is stopped.

What we claim is:

1. The combination of a boiler feed pump, a

source of supply therefor, and a compound feeding means associated therewith, said feeding means having a chamber for containing compound lying above the maximum level of said source of supply, and a conduit connecting the 5 high pressure side of said pump to the low pressure side thereof in which said chamber is included for circulating feed water through the latter to prepare a water treating solution.

2. The combination of a feed water pump, a 10 source of supply for said pump, a chamber containing water treating compound, a conduit interconnecting the high and low pressure sides of said pumps and having said chamber interposed therein for circulating feed water therethrough 15 to form a water treating solution, a valve in said conduit, means opening and closing said valve, a choke in said conduit, and means fixed to said valve for agitating fluid in said choke when the position of said valve is changed. 20

3. The combination as set forth in claim 1 together with means for causing the chamber for containing compound to be drained whenever the feed pump is shut down.

4. The combination of a feed water pump, a 25 source of supply for said pump, and compound feeding means associated therewith comprising a receptacle containing water treating compound, a conduit connected to said pump and receptacle for supplying feed water to the latter to prepare 30 a water treating solution from the compound therein, a valve controlling said conduit and located therein between said pump and receptacle, means associated with said pump and said valve arranged to open said valve whenever the pump 35 is operating, and means for automatically closing said valve when the pump is shut down.

5. The combination of a feed water pump, a source of supply for said pump and compound feeding means, comprising a receptacle containing 40 water treating compound, a conduit connecting the outlet side of said pump to the inlet side thereof and having said receptacle interposed therein for circulating feed water through said receptacle to prepare a water treating solution 45 from the compound in the latter and return it to the inlet side of said pump, a valve controlling said conduit and located therein between the outlet side of said pump and said receptacle, means associated with said pump and said valve arranged to open said valve whenever the pump 50 is operating, and means for automatically closing said valve when pump is shut down.
